UNITED STATES PATENT OFFICE.

JOHN STEMBER, OF NEW YORK, N. Y.

LADY'S POCKET-BOOK.

1,307,324.

Specification of Letters Patent. Patented June 17, 1919.

Application filed December 31, 1918. Serial No. 269,075.

To all whom it may concern:

Be it known that I, JOHN STEMBER, a citizen of the United States, and a resident of the city of New York, borough of Manhattan, in the county and State of New York, have invented a new and Improved Lady's Pocket-Book, of which the following is a full, clear, and exact description.

The object of the invention is to provide a new and improved lady's pocketbook having a bill pocket arranged in such a manner that the user can readily place bills therein and close the pocket to render the bills invisible on opening the pocketbook, and to prevent such bills from accidentally dropping out of the pocketbook and become lost. Another object is to hold the bills in flat condition one on top of the other thus enabling the owner of the pocketbook to readily select a bill of the desired denomination for removal from the bill pocket whenever it is desired to use such bill. Another object is to provide a bill pocket which is not unduly bulky or which interferes with the usual compartments of the lady's pocketbook.

With these and other objects in view, the invention consists of certain novel features of construction, as hereinafter shown and described and then specifically pointed out in the claims.

A practical embodiment of the invention is represented in the accompanying drawings forming a part of this specification, in which similar characters of reference indicate corresponding parts in both views.

Figure 1 is a front elevation of the pocketbook with the main closing flap and its bill pocket in open position, part of the auxiliary closing flap for the bill pocket being broken out; and

Fig. 2 is a cross section of the same on the line 2-2 of Fig. 1.

The body 10 of the lady's pocketbook is of usual construction and is provided with a number of compartments 11 adapted to contain various articles such as handkerchiefs, writing pad and the like, and one of the

compartments is adapted to contain a coin purse 12 and another compartment is adapted to contain a mirror 13, as indicated in Fig. 1, but I do not limit myself to the particular arrangement of the compartments 11 or the articles they are to contain. The lady's pocketbook is further provided with a closing flap 15 which preferably forms a continuation of the back 16 of the body 10, and on the said back 16 and the main closing flap 15 is arranged a handle 17 for conveniently carrying the pocketbook about.

On the inner face of the main closing flap 15 is arranged a bill pocket 20 of a depth and length corresponding to the size of a regular United States bill 21, as indicated in Fig. 1, to allow of storing one or a number of such bills in the pocket 20 in flat superimposed condition. The bill pocket 20 is made of two pieces 22 and 23, of which the piece 22 is secured at its outer edge by stitches 24 or other fastening means to the outer edge of the back 16, and the sides of this piece 22 are fastened by stitches 25 to the sides of the main closing flap 15. The other piece 23 of the bill pocket 20 overlies the piece 22 and is fastened at its inner edge by glue or other fastening means to the inner edge of the other piece 22, as indicated at 26 in the drawings. The piece 23 is also secured at its sides by the stitches 25 to the sides of the piece 22, and the said piece 23 terminates at its outer edge a distance from the free outer end of the back 15 thus providing an open mouth 27 for the pocket 20 to allow of conveniently placing the bills 21 into the pocket or removing the same therefrom whenever it is desired to do so. By reference to Fig. 2 it will be noticed that the piece 22, which is practically the back of the pocket 20, forms with the covering flap 15 a second pocket 30, the mouth 31 of which however is adjacent the inner end of the covering flap 15. This pocket can be used for storing thin flat articles.

In order to close the mouth 27 of the bill

5 pocket 20 use is made of an auxiliary closing flap 40 secured at its outer edge by the stitches 24 to the outer edge of the main covering flap 15, and the auxiliary closing flap 40 and the piece 23 are provided with coacting fastening devices 41 and 42 such as stud and socket members of snap fasteners to permit of locking the auxiliary flap 40 in closed position. It is understood that 10 normally the auxiliary closing flap 40 is in closed and locked position thus completely hiding the bills 21 contained in the bill pocket 20. When the user opens the pocket-book by swinging the covering flap 15 upward into open position the bills 21 are not displayed and are not liable to accidentally drop out of the pocket 20. When the user desires to remove any one of the bills 21 it is only necessary to unlock the auxiliary 15 closing flap and to swing the same upward to allow the user to obtain access to the bills at the open mouth 27. One or more bills can now be readily removed from the pocket 20 without disturbing the other bills and after 20 this has been done the user again closes the auxiliary flap 40 to hold the remaining bills in position in the bill pocket 20.

In practice, the flap 15 has its sides and outer edge formed into bent over flanges 30 held in place by the stitches 25 to give a desired finish to the pocket book especially by covering the raw edges of the pieces 22 and 23 and that of the flap 40.

The piece 22 of the bill pocket 20 has its 35 upper portion disconnected from the sides of the closing flap 15 to allow of readily bending this upper portion outward to gain convenient access to the bill pocket for the insertion or removal of the bills. It will 40 also be noticed that the sides of the piece 22 are not liable to be torn on opening the bill pocket.

Having thus described my invention, I claim as new and desire to secure by Letters 45 Patent:—

1. A lady's pocketbook, comprising a body having compartments and a main closing flap forming an extension of the back of the said body and adapted to close the 50 said compartments and overlie the front of the said body, a bill pocket on the inner face of the said main closing flap, and said pocket being formed of two pieces, one of which is secured to the flap and the other to the 55 inner end and sides of the first piece with its outer end terminating a distance from the outer end of the flap to form a mouth, the said bill pocket being of a depth and width corresponding approximately to that of a bill to accommodate a number of superimposed bills in flat condition, and an auxiliary closing flap attached to the free end of the said flap and adapted to close the mouth of the said bill pocket and overlie the front 60 thereof.

2. A lady's pocketbook, comprising a body having compartments and a main closing flap forming an extension of the back of the said body and adapted to close the said compartments and overlie the front of the said body, a bill pocket on the inner face of the said main closing flap and having its mouth adjacent the free end of the said main closing flap, the said bill pocket being of a depth and width corresponding approximately to that of a bill to accommodate a number of superimposed bills in flat condition, a second pocket between the bill pocket and the flap and having its mouth at the bottom of the bill pocket, an auxiliary closing flap attached to the free end of the said flap and adapted to close the mouth of the said bill pocket and overlie the front thereof, and fastening members on the said auxiliary closing flap and the front of the said bill pocket to lock the auxiliary flap in closed position. 75 80 85

3. A lady's pocketbook, comprising a body having compartments and a main closing flap adapted to swing over onto the front of the body to close the compartments, a double pocket arranged on the inner face of the said main flap and formed of two pieces overlying one the other, the rear piece being attached at its outer edge and at the sides to the outer edge and the sides of the main closing flap, the inner edges of the said pieces being fastened together and the sides of the outer piece being attached to the sides of the said main closing flap thus providing an inner and an outer pocket, the pockets extending the width of the flap and having their mouths at opposite ends, the outer pocket being of a depth and width corresponding approximately to the size of a bill 90 95 100 thus providing a bill pocket for the storage of bills, the outer edge of the said outer piece terminating a distance from the outer edge of the main flap to provide an open mouth for insertion or removal of the bills, and an auxiliary closing flap attached at its outer edge to the outer edge of the said main flap and adapted to close the said open mouth of the said bill pocket. 105 110 115

4. A lady's pocketbook, comprising a body having compartments and a main closing flap adapted to swing over onto the front of the body to close the compartments, a double pocket arranged on the inner face of the said main flap and formed of two pieces overlying one the other, the rear piece being attached at its outer edge and at the sides to the outer edge and the sides of the main closing flap, the inner edges of the said pieces being fastened together and the sides of the outer piece being attached to the sides of the said main closing flap thus providing an inner and an outer pocket, the pockets extending the width of the flap and having their mouths at opposite ends, the outer pocket 120 125 130

being of a depth and width corresponding approximately to the size of a bill thus providing a bill pocket for the storage of bills, the outer edge of the said outer piece terminating a distance from the outer edge of the main flap to provide an open mouth for insertion or removal of the bills, an auxiliary

closing flap attached at its outer edge to the outer edge of the said main flap and adapted to close the said open mouth of the said bill pocket, and fastening means for fastening the said auxiliary closing flap to the said outer piece.

JOHN STEMBER.
